ELECTRICALLY CONTROLLED VALVE

Charles C. Hansen, Forest Park, Ill., assignor to
Refrigerating Specialties Company, Chicago,
Ill., a corporation of Illinois

Application May 12, 1930, Serial No. 451,615

7 Claims. (Cl. 137—139)

The invention relates to electrically controlled valves.

The primary object of the invention is to provide an improved electrically controlled valve which is adapted primarily for use in controlling the flow of refrigerant in refrigerating systems wherein full closing and opening cycles of the valve are desired; in which a hammer blow is imparted to a pilot valve to control the movement of the main valve by the pressure of the fluid; in which the necessity of stuffing boxes is dispensed with; in which the pilot-valve and valve are built as a self-contained unit which is adapted for use on different valve pistons, and are easily assembled therewith; in which a blow from the armature of the magnet and the pressure of the fluid through a secondary valve are conjointly utilized to close positively, but gently, the main valve; in which the helix of the magnet and the conductors therefor are enclosed in a moisture-proof housing; and which includes means for manual control independent of the electric control. Other objects of the invention will appear from a consideration of the following detailed description.

The invention consists in the several novel features which are, hereinafter set forth and are more particularly defined by claims at the conclusion hereof.

In the drawing which accompanies and forms a part of this specification or disclosure and in which like numerals of reference denote corresponding parts throughout the several views: Fig. 1 is a vertical sectional view showing a valve embodying the invention in its open position. Fig. 2 is a similar view showing the valve in its closed position. Fig. 3 is a section on an enlarged scale through the valve piston and the secondary piston and pilot valves.

The invention is exemplified in an electrically controlled valve comprising a casing or body 5 which is provided with flanges 8 whereby it may be bolted to flanges on the ends of pipes or fittings, an inlet 6 for fluid under pressure, an outlet 7, and an integral wall 9 which separates the inlet from the outlet and is provided with an opening 10 through which fluid may pass from the inlet to the outlet. A main valve piston 11 comprises a cylindrical wall 11^a, an integral bottom wall 11^b, and a ring 13 set into a recess in the bottom face of wall 11^b and removably held thereon by a nut 14. Ring 13 is formed of suitable material to form a valve-seat, and is adapted to engage a coacting seat on the cross-wall 9 to cut off communication between the inlet 6 and the outlet 7.

Piston 11 fits and is slidable vertically in a cylinder 12 which is formed in the casing 5 and communicates with the inlet side thereof. The upper end of the piston 11 is open. A port 16 is formed in the lower portion of the piston to admit fluid under pressure to the chamber 11^c in the top of the piston and into the cylinder 12 in which the piston slides. When the piston is closed, it will be held against its seat on wall 9 by the pressure of the fluid in the inlet side of the valve body. Piston 11 constitutes the main closure for cutting off communication between the inlet and outlet sides of the valve casing.

A casing 17 is formed with a cylinder 18 for a secondary slidable valve-piston 22 and has a bottom wall seated on the top face of the bottom-wall 11^b of the main piston 11. It has an integral stem 19 which extends through wall 11^b and ring 13, and is provided with a vertical port 21. Nut 14 is threaded to the lower end of said stem and clamps and removably secures the casing 17 and the ring 13 to the piston 11. Secondary valve piston 22 fits and is vertically slidable in the cylinder 18, and is adapted to seat on the bottom wall of casing 17 to close the upper end of port 21 to stop the flow through the main valve-piston. Ports 20 extend through the side wall of the secondary valve-casing 17 to admit fluid from the chamber 11^c in piston 11 into the cylinder 18 below piston 22. Vertical port 21 in stem 19 permits the fluid in piston 11 to pass therethrough under control of the secondary valve-piston 22. A ring 23 in the lower face of casing 17 is adapted to seat on the bottom of the casing to control the flow through port 21. A nipple 24 with a port 31, removably secures ring 23 in casing 17 and has a screw-threaded stem 24^a which is threaded to the piston 22. The upper end of casing 17 is closed by a head 25 which has a port 25^a therein to admit fluid to the upper end of cylinder 18 and piston 22. A cylinder 26 is formed in the secondary valve piston 22 and a pilot piston or plunger 27 is slidable in said cylinder. Oblique ports 28 are formed in piston 22 to admit fluid to the lower end of cylinder 26 and piston 22. Pilot plunger 27 is provided in its lower end with a seat 30 to engage the upper end of nipple 24, to close vertically through-port 31 and control the flow of fluid through secondary valve piston 22. Plunger 27, when lowered, is adapted to close the lower end of oblique ports 28, and to close port 31 in nipple 24.

Pilot plunger 27 is controlled by an electromagnet of the solenoid type which comprises an armature 32 and a helix 33. A head 34 is remov-

ably secured by bolts 35 to the upper end of casing 5. Helix 33 is contained in a cylindrical housing 35^a formed at, and integral with, the upper end of said head. A tube 36, disposed between the helix and the armature, has its lower end threaded into the neck of said head, and is formed of suitable non-corrodible metal, such as "Allegheny" metal which is adapted to resist the action of the refrigerant. Armature 32 is slideable in tube 36 and is enclosed thereby. A screw-plug 37 is threaded into and closes the upper end of tube 36, and its lower end serves as a stop for limiting the upward movement of the armature 32 when the helix 33 is energized. A cap 38 fits over the housing 33 and encloses the top of the helix. A nut 39, threaded to the upper end of plug 37, is adapted to jamb the cap 38 on the top of the housing 35^a to seal the helix. An angular opening 40 is formed in the plug 37 for the conductors leading to and from the helix, and the upper end of the nut 39 is usually filled with sealing material around the conductors to seal the housing. This is of importance when the valve is used for lines which become frosted as in refrigerating systems. By this construction, the tube which guides the armature will be closed, so that no stuffing box is necessary for the connection between the solenoid and the valve, and the use of non-corrodible metal makes it possible to use the device for refrigerating systems.

40 Rod 41, secured to the lower end of armature 32, extends through head 25 at the upper end of casing 17, and through a cap 42 which is threaded into the upper end of the pilot plunger 27. A head or abutment 43 is formed on the lower end of rod 41 to engage cap 42 to lift said plunger and to strike a screw plug 44 in the plunger to lower the latter. Plug 44 is threaded to the inside of plunger 27. This construction exemplifies a lost motion connection between the armature 32 and the pilot plunger 27 for imparting hammer blows to the pilot, and whereby the pilot will be shifted to control the flow of fluid under pressure through piston 22, ports 28, and the port 31 in the nipple 24.

45 The operation will be as follows: Assuming the valve to be closed, as shown in Fig. 2, fluid under pressure will pass through port 16 to exert down-pressure on the valve piston 11, and hold it closed, so that opening 10 will be closed. Fluid will also pass through port 25^a in the head 25 into cylinder 18 to exert down-pressure on and hold the valve-piston 22 so its ring 23 will seat on the bottom of cylinder 18 and close port 21 in stem 19. Fluid in the top of cylinder 18 will also exert pressure 50 on the top of pilot-plunger 27 and force it downwardly to close the lower ends of oblique ports 28, and to hold its seat 30 on the upper end of nipple 24 to close port 31 in said nipple. The weight of armature 32 will also be applied through head 43 to hold the pilot plunger down. As a result the main valve piston 11, the secondary piston 22 and the pilot-plunger will all be held closed to prevent the flow of fluid through opening 10 in the valve-casing, port 21 in the cylinder 17 and port 31 in the secondary valve-piston. Helix 33 will be deenergized, and its armature 32 will be held in its lowered position by gravity, the head 43 of rod 41 resting on plug 44 to hold the pilot plunger 27 seated on the nipple 24 and close the port 31 in said nipple. When the valve is to be 60 opened, helix 33 will be energized which will lift the armature 32. The head 43 on rod 41 will, after it has travelled upwardly freely from plug 44 to cap 42, impart a hammer blow to and lift the

5 pilot-plunger 27 sufficiently to open the port 31 in the nipple 24. Fluid will then pass from the cylinder 12 and the chamber 11^c in valve-piston 11 through diagonal ports 28 to the underside of the plunger 27, and into cylinder 26, and from said cylinder it will pass through port 31 in nipple 24 to the outlet side of the casing 5. This will reduce the pressure on the upper end of the piston 22, and will release the secondary valve-piston 22. The pressure exerted on the lower end of the 10 secondary valve piston 22 by fluid admitted through ports 20 will lift said piston and raise ring 23 off its seat on the casing 17. This will open the port 21 so fluid can pass from the cylinder 18 through opening 10 into the outlet side 15 of valve-casing 5. The preponderant pressure of the fluid on the underside of the valve-piston 11 will then lift it to its fully open position shown in Fig. 1, and the pressure on the underside of valve piston 22 will hold it in its open position 20 while the armature 32 remains raised, to permit the fluid to flow freely through opening 10 into the outlet 7. When the valve is to be closed, the circuit through helix 33 will be opened to deenergize the helix 33 which will cause the armature 32 25 to fall by gravity. Initially, the drop of the armature will be free until its head 43 strikes the plug 44 in pilot-plunger 27. The impact from this drop of the armature will impart a downward blow to the pilot plunger 27 to close the ports 28 30 and so its seat 30 will close the port 31 in nipple 24. This will stop the flow of fluid through the secondary valve-piston and will also force it downwardly so its ring 23 will close port 21 in the casing 17. Pressure will then be exerted on the 35 top of piston 22 and the main piston 11, and flow of fluid through the main valve piston 11 will be interrupted, and, thereupon, the main valve piston will be closed and held by the pressure of the fluid as before described.

40 In this operation, when the armature 32 is released, the force acquired from the velocity of its drop will impart a kick or blow to the pilot plunger 27 and to the secondary valve piston 22, which will bring the secondary valve-piston to its seat, 45 and the consequent velocity jolt imparted to the main piston valve 17, together with the gravity of all of the moving parts, will cause the main valve, as fast as fluid can replace the partial vacuum caused by the downward movement of the piston 50 valve, to seat on wall 19 and close port 10, and thus cause the main valve piston fully and positively, but gently to close.

45 In some instances, it is desired to control the valve manually, and for this purpose, there is provided a stem 50 which is screw-threaded to a nipple 51 which is screw-threaded into the bottom of the casing 5. Stem 50 is provided with a handle 52 outside of said casing, whereby it may be turned to raise and lower the stem. The latter 60 passes through a packing box 53 in the nipple. The upper end of the stem 50 is adapted to pass through the opening 10 in wall 9 and nipple 19 to engage the nipple 24 and unseat the secondary valve piston 22 so fluid will pass into cylinder 18 65 to raise valve piston 22 and permit the fluid to raise the main valve piston 11. When the stem 52 is lowered, the valve pistons will close, as before described.

70 The invention exemplifies an electro-magnet- 70 ically controlled valve: in which a pilot, having a lost motion connection with the armature, has hammer blows imparted thereto, and controls the flow of fluid through the main valve piston, so that the force and impact of the armature are 75

utilized to shift the plunger and secondary valve for controlling the flow through the secondary and the main valve pistons; in which the main and secondary valve pistons are held closed by the pressure of the fluid; in which the pressure of the fluid is utilized to supplement the force of the armature to open the main and secondary valve pistons; in which full strokes are effectively but gradually imparted to the main valve; which is adapted for refrigerating systems in which the use of packing boxes for the valve ports is dispensed with; in which the helix of the magnet is sealed so that the valve is adapted for use where the lines become frosted; in which provision is made for manually shifting the secondary valve piston to open the main valve piston when occasion should arise; in which secondary valve piston, the pilot plunger, and the armature form a unitary structure which can be easily mounted, and interchangeably used on different valves; and which can be produced at a low cost.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In an electrically controlled valve of the character described, the combination of a casing provided with an inlet and an outlet for fluid under pressure, a main valve piston for controlling the flow of the fluid between the inlet and outlet, slidably mounted in the casing and provided with a port for permitting a portion of its fluid to pass therethrough from the inlet to the outlet, a secondary valve piston for controlling the flow of fluid through the port in the main valve piston, an electro-magnet comprising an armature for controlling said secondary valve piston, and manually operable means adapted to pass through the port in the main valve piston, for shifting the secondary valve piston in order to effect opening of the main valve piston without use of the magnet.
2. In an electrically controlled valve of the character described, the combination of a casing provided with an inlet and an outlet for fluid under pressure, a hollow main valve piston for controlling the flow of fluid between the inlet and outlet, adapted to be held in its closed position by the pressure of the fluid and provided with a port for permitting a portion of the fluid to pass therethrough in order to release the pressure of the fluid thereon and permit it to move into its open position, a hollow, secondary valve piston for controlling said port slidably mounted within the main valve piston and adapted to be held in its closed position by the pressure of the fluid, and provided with port means for permitting fluid to pass therethrough from the inlet to the aforesaid port in the main valve piston for the purpose of allowing said secondary valve to move into its open position, a pilot plunger slidably mounted in the secondary valve piston and arranged to control the flow of fluid through said port means of the secondary valve piston, and means for actuating the pilot plunger comprising an electromagnet embodying an armature with a stem and a lost motion operating connection between the stem and the pilot plunger operative when the magnet is energized to impart a hammer blow to the plunger so as to shift the latter into its open position.
3. In an electrically controlled valve, the combination of a casing having a head at the top portion thereof and provided with an inlet and an outlet for fluid under pressure, a valve piston for controlling the flow of fluid between the inlet and outlet mounted slidably in the casing and provided with a port for permitting fluid to pass therethrough, means for controlling said port, a vertical tube secured in the head and communicating by way of the head with the portion of the casing having the valve piston, a magnet comprising a helix around the tube and an armature movably confined in the tube and connected to operate the controlling means, a plug secured in and serving to close the upper end of the tube and having an externally threaded portion above the tube with an angular passage therein for the conductors for the helix, a housing on the head and around the helix, a cap for said housing having an opening therein through which extends the externally threaded portion of the plug, and a nut on said externally threaded

and outlet, adapted to be held in its closed position by the pressure of the fluid and provided with a port for permitting a portion of the fluid to pass therethrough in order to release the pressure of the fluid thereon and permit it to move into its open position, a hollow, secondary valve piston for controlling said port slidably mounted within the main valve piston and adapted to be held in its closed position by the pressure of the fluid and provided with port means for permitting fluid to pass therethrough from the inlet to the aforesaid port in the main valve piston for the purpose of allowing said secondary valve to move into its open position, a pilot plunger slidably mounted in the secondary valve piston and arranged to control the flow of fluid through said port means of the secondary valve piston, a magnet comprising an armature, and a lost motion operating connection between the armature and the pilot plunger whereby the latter is actuated with a hammer blow when the magnet is energized.

4. In an electrically controlled valve of the character described, the combination of a casing provided with an inlet and an outlet for fluid under pressure, a hollow main valve piston for controlling the flow of fluid between the inlet and outlet, adapted to be held in its closed position by the pressure of the fluid and provided with a port for permitting a portion of the fluid to pass therethrough in order to release the pressure of the fluid thereon and permit it to move into its open position, a hollow, secondary valve piston for controlling said port slidably mounted within the main valve piston and adapted to be held in its closed position by the pressure of the fluid, and provided with port means for permitting fluid to pass therethrough from the inlet to the aforesaid port in the main valve piston for the purpose of allowing said secondary valve to move into its open position, a pilot plunger slidably mounted in the secondary valve piston and arranged to control the flow of fluid through said port means of the secondary valve piston, and means for actuating the pilot plunger comprising an electromagnet embodying an armature with a stem and a lost motion operating connection between the stem and the pilot plunger operative when the magnet is energized to impart a hammer blow to the plunger so as to shift the latter into its open position.

5. In an electrically controlled valve, the combination of a casing having a head at the top portion thereof and provided with an inlet and an outlet for fluid under pressure, a valve piston for controlling the flow of fluid between the inlet and outlet mounted slidably in the casing and provided with a port for permitting fluid to pass therethrough, means for controlling said port, a vertical tube secured in the head and communicating by way of the head with the portion of the casing having the valve piston, a magnet comprising a helix around the tube and an armature movably confined in the tube and connected to operate the controlling means, a plug secured in and serving to close the upper end of the tube and having an externally threaded portion above the tube with an angular passage therein for the conductors for the helix, a housing on the head and around the helix, a cap for said housing having an opening therein through which extends the externally threaded portion of the plug, and a nut on said externally threaded

portion of the plug for clamping the cap on the housing.

6. In a valve of the character described, the combination of an elongated casing adapted to extend horizontally and embodying an inlet at one end and an outlet at its other end for fluid under pressure, a cross-wall between said inlet and outlet forming an inlet compartment for the fluid in the top central portion of the casing and forming an outlet compartment for the fluid in the bottom central portion of the casing and having the central portion thereof extending horizontally and provided with a vertical aperture for permitting the fluid to pass from the inlet compartment to said outlet compartment, and an upwardly extending part forming a vertical cylinder above the inlet compartment and directly over said aperture; means for admitting fluid from the inlet compartment into the cylinder; a cup-shaped valve piston adapted to control the flow of fluid from the inlet compartment to the outlet compartment and comprising a cylindrical side wall of uniform diameter from one end thereof to the other slidably vertically in the cylinder and a circular bottom wall connected to and formed integrally with the lower end of the side wall and having a port in the central portion thereof aligned with the aperture and an annular cavity around the port and a packing ring in the cavity for engaging the aperture forming portion of the cross-wall and also having the outer margin thereof tapered downwardly to form an inclined annular surface around the ring, said piston being adapted when the port is closed and in response to the pressure of fluid in the cylinder to slide downwards into a closed position wherein the packing seats against the aforesaid aperture forming portion of the cross-wall and being further adapted when the port is open and the pressure of the fluid in the cylinder is thereby released to slide upwards into an open position in response to the pressure of the fluid in the inlet compartment operating against said annular surface; means mounted in and movable with the piston for opening and closing the port; and means disposed outside of the casing for actuating the port opening and closing means.

7. In a valve of the character described, the

combination of an elongated casing adapted to extend horizontally and embodying an inlet at one end and an outlet at its other end for fluid under pressure, a cross-wall between said inlet and outlet forming an inlet compartment for the fluid in the top central portion of the casing and forming an outlet compartment for the fluid in the bottom central portion of the casing and having the central portion thereof extending horizontally and provided with a vertical aperture for permitting the fluid to pass from the inlet compartment to said outlet compartment, and an upwardly extending part forming a vertical cylinder above the inlet compartment and directly over said aperture; means for admitting fluid from the inlet compartment into the cylinder; a cup-shaped valve piston adapted to control the flow of fluid from the inlet compartment to the outlet compartment and comprising a cylindrical side wall of uniform diameter from one end thereof to the other mounted for vertical sliding movement in the cylinder and a circular bottom wall connected to and formed integrally with the lower end of the side wall and having a port in the central portion thereof aligned with the aperture and an annular cavity around the port and a packing ring in the cavity for engaging the aperture forming portion of the cross-wall and also having the outer margin thereof tapered downwardly to form an inclined annular surface around the ring, said valve piston having a hole leading from said annular face and extending through the bottom wall for admitting fluid from the inlet compartment into the cylinder and being adapted when the port is closed and in response to the pressure of fluid in the cylinder to slide downwards into a closed position wherein the packing seats against the aforesaid aperture forming portion of the cross-wall and being further adapted when the port is open and the pressure of the fluid in the cylinder is thereby released to slide upwards into an open position in response to the pressure of the fluid in the inlet compartment operating against said annular surface; means mounted in and movable with the piston for opening and closing the port; and means disposed outside of the casing for actuating the port opening and closing means.

CHARLES C. HANSEN.
